(57) CLAIM

The ornamental design of a fork and grapple attachment, substantially as shown and described.

DESCRIPTION

FIG. 1 is a side view of a fork and grapple attachment embodying my new design and showing a moved position of the grapple;

FIG. 2 is a front view thereof;

FIG. 3 is a top view thereof;

FIG. 4 is a bottom view thereof; and,

FIG. 5 is a back view thereof.

The broken line showing is for illustrative purposes only and forms no part of the claimed design.

1 Claim, 5 Drawing Sheets

FIG. 1 -
